C. E. WERNER.
DISTILLING APPARATUS.

No. 10,463.

Patented Jan. 24, 1854.

UNITED STATES PATENT OFFICE.

CARL E. WERNER, OF NEWCASTLE, ILLINOIS.

IMPROVEMENT IN DISTILLING APPARATUS.

Specification forming part of Letters Patent No. 10,463, dated January 21, 1854.

To all whom it may concern:

Be it known that I, CARL E. WERNER, of Newcastle, Logan county, Illinois, have invented new and useful Improvements in Distilling Apparatus for the Manufacture of Alcohol; and I do hereby declare the following to be a full, clear, and exact description thereof, reference being had to the annexed drawing, making part of this specification.

The objects of my invention are the guarding the discharge-openings of the wash-pipes from interruption by the entering steam; the drawing of the beer or wash from the lower-most stratum in every case, so as to carry down that part which contains the least amount of alcohol without reducing the desired level of the liquid.

In the accompanying drawing my plan of alcoholic distilling apparatus is represented by a vertical section.

a is a wooden trough or tube conveying the wash to the feed-pipe *b*. This trough or tube incloses the vapor-pipe *c*, leading from the doubler *d*. The beneficial effect of this arrangement is twofold: first, the beer is heated up to about 180° Fahrenheit before entering the still, and, secondly, such of the watery particles not retained by the doubler are condensed upon the sides of the vapor-pipe and returned by pipe or pipes *e* as singles to the doubler, and to facilitate this reflux of the singles the beer-trough is placed at a slight backward inclination. I consider this backwardly-inclined arrangement of the vapor-pipe and the inclosing beer-trough far preferable to any mode of heating by the beer, in which the results of condensation in this part of the vapor-pipe are conducted to the worm.

In order that the entering wash and the departing vapor may have the full reciprocal effect upon each other, the inclosed pipe may be much lengthened and may be in a zigzag or spiral form, but is here abridged for convenience of delineation. This apparatus entirely dispenses with the cold-water condenser and the loss of heat consequent thereon.

The pipes *f*, which conduct the beer and singles from the upper to the lower chambers, are so constructed that, while they only let off the contents as they rise above a certain level, the lowest stratum of fluid is first discharged, being that which contains the least amount of alcohol. These objects I effect by

encircling the pipe *f* with a tube, *g*, which rises above the pipe to a height greater than any possible ebullition of the liquid, and descends to precisely such depth as it is desired to discharge from. The entrance or summit of the pipe *f* is, as usual, placed at such a height as to determine at what elevation within the chamber the wash shall stand. The lower extremity of the pipe *f* stops a little short of the floor of the chamber below, and is surrounded by a rim, *h*, which rises from the floor to a sufficient height above the bottom of the pipe *f* to prevent the entrance of any of the steam within the said pipe, which steam (rising by ebullition from the lower stratum of the liquid and seeking the most direct upward channel) would tend to disturb the regular action of the apparatus. Across one or more of the chambers runs a double wall, *i*, the two vertical partitions of which close above the pipe communicating with the vapor of the subjacent chamber. This wall is more effectual than the usual cylindrical hoods, as it partially divides the chamber into two compartments, and the wash, passing beneath the wall from the receiving to the discharging compartment, comes intimately in contact with the steam and vapor escaping from the chamber below, and this tends to the condensation of the watery particles and the vaporization of the alcoholic portion of the liquid.

j is a try-worm for ascertaining the condition of the vapor from time to time, and may be placed in connection with either of the two lower chambers, as may be deemed or found to be preferable.

k l m n o is a peculiar arrangement of discharge pipe and valve combined, and consists of a siphon-pipe, *K*, having a small air-vent, *l*. This siphon is fixed by its longer limb to a slide-valve or sluice-plate, *m*, having two apertures, *n o*, one at the extremity of the longer limb and the other to one side of it, and according as one or the other of these apertures is brought over the discharge-pipe *f* the chamber is at pleasure either kept supplied to the height of the bend of the siphon or emptied.

The object of the air-vent *l* is that there may be no lodgment of air or vapor in the bend or any passage of air through the shorter limb, as such lodgment or passage of air would tend to interrupt the free discharge of the liquid. The slop-tub *p* receives the steam-pipe *q*, and com-

municates by a neck, *r*, with the lower chamber of the still. By this means any alcohol remaining in the slop is forced back again into the still. The strike-valve *s* is, by a rod, *u*, connected to a float, *t*, so that whenever the stop rises above the desired height the valve is lifted and some of the lower stratum of slop is discharged.

What I claim as new and of my invention, and desire to secure by Letters Patent, is—

1. Surrounding the entrance of the conducting-pipe *f* with an open tubular screen, *g*, which rises above the pipe-entrance to a height greater than any possible ebullition of the liq-

uid, and terminates below at such portion of the liquid as it is desired to discharge from.

2. The rim *h*, rising from the floor of the chamber and encircling the discharging-opening of the conducting-pipe *f*, for prevention of the interference of steam with the discharging action of said pipe.

In testimony whereof I have hereunto set my hand before two subscribing witnesses.

CARL ERNST WERNER.
